CUTTING TOOL

Kunio A. Sumida, Los Angeles, Calif., assignor to
Leonard U. Shapiro, St. Paul, Minn.

Filed Feb. 25, 1971, Ser. No. 119,070

Term of patent 14 years

Int. Cl. D8—03

U.S. Cl. D8—61

FIG. 1 is a perspective view of a cutting tool illustrating a new design therefor;

FIG. 2 is a side elevational view thereof;

FIG. 3 is a bottom plan view of the cutting tool;

FIG. 4 is a view of the rear elevation thereof; and

FIG. 5 is a front view thereof.

I claim:

The ornamental design for a cutting tool, substantially as shown.
